(57) **CLAIM**

The ornamental design for an auger assembly, as shown and described.

DESCRIPTION

FIG. 1 is a top plan view of the first embodiment of an auger assembly embodying my design;

FIG. 2 is a bottom plan view thereof;

FIG. 3 is a rear elevational view thereof;

FIG. 4 is a front plan view thereof;

FIG. 5 is a left end view thereof as seen along lines 5—5 of FIG. 1;

FIG. 6 is a right end view thereof as seen along lines 6—6 of FIG. 1;

FIG. 7 is a top plan view of a second embodiment of my auger assembly design;

FIG. 8 is a bottom elevational view thereof;

FIG. 9 is a rear elevational view thereof;

FIG. 10 is a front plan view thereof;

FIG. 11 is a left end view thereof as seen along lines 11—11 of FIG. 7; and,

FIG. 12 is a right end view thereof as seen along lines 12—12 of FIG. 7.
